(57) **CLAIM**

The ornamental design for an inhaler, as shown and described.

DESCRIPTION

FIG. 1 is a perspective view of an inhaler showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view thereof in an open state;

FIG. 9 is a front elevation view thereof in an open state; and,

FIG. 10 is a right side elevation view thereof in an open state.

The broken lines shown in the drawings illustrate portions of the article and form no part of the claimed design.
